GUIDE DEVICE FOR KEY-OPENED CANS

Paul H. Patterson, Columbus, Ohio

Application July 20, 1954, Serial No. 444,497

1 Claim. (Cl. 220—52)

This invention has particular reference to an improved guide device for use in association with sealed key-opened metallic cans of the type commonly employed in the packaging and preservation of various food products.

Such key-operated cans are formed to include cylindrical sheet-metal bodies in which are incorporated adjacent to the top of each can a removable strip. In use, a vertically held manually operated key having a slotted shank is disposed at the side of such a can, contiguous to the top thereof, with a free end of the can wall strip inserted in the opening of the key shank. Then, upon rotation of the key about the long axis of its shank, the strip is caused to be wrapped spirally around the key shank and the key caused to move circumferentially around the can as the strip is torn free from the side wall formation of the can. These operations are pursued until the strip is completely torn free from the side wall formation and the top of the can thereby separated from the side wall thereof so that the edible contents of the can may be readily removed and utilized as desired. It is a matter of common knowledge that in the opening of such strip-sealed cans it is often difficult to maintain the spiral convolutions of the strip, as the latter is being wound about a key shank, in a common horizontal plane until the strip has been fully removed from a can body. Unless such a plane is maintained the key becomes ineffective in performing its intended functions. Therefore, it is a common practice to hold and guide the spiral strip windings in one's fingers during the opening of a can with likelihood of incurring physical injury thereof.

Accordingly, it is one of the leading objects of the present invention to provide a guide-forming appliance to assist an operator in the opening of a key-actuated strip-sealed food-containing can, and wherein the appliance is so formed that when operatively mounted on such a key-opened can it will be necessary only for the operator to rotate the key in producing guided winding of the sealing strip about its shank, this being accomplished in a manner precluding slippage of the windings relative to the key shank.

Another object is to provide a simple, readily employed and positively operating guide device adaptable readily to cans of varying size and construction and which provides an improvement generally in the field to which it is specifically adaptable.

For a further understanding of the invention, reference is to be had to the following description and the accompanying drawing, wherein:

Fig. 1 is a top plan view of key-opened can, and disclosing my improved strip-guiding device mounted thereon;

Fig. 2 is a side elevational view thereof;

Fig. 3 is a front elevational view;

Fig. 4 is a side elevational view disclosing the guide device when inverted and adapted to a can having a sealing strip positioned more closely to the top of the can than the strip used on the can of Fig. 3;

2

Fig. 5 is an enlarged detail vertical sectional view taken on the line 5—5 of Fig. 1;

Fig. 6 is a detail horizontal sectional view on the line 6—6 of Fig. 5;

Fig. 7 is an enlarged detail sectional view on the line 7—7 of Fig. 5.

Referring more particularly to the drawings, there has been disclosed at 10 a conventional strip-sealed can of the type employed quite commonly in the anti-oxidation packaging of foodstuffs, such as meats, coffee, nuts and the like. Such cans employ cylindrical side walls 11 closed by top and bottom walls 12 and 13, respectively. Adjacent to the top wall thereof, each of said cans has its side wall formed with a separable sealing strip 14 which when the can is sealed to protect the contents thereof forms a component part of the cylindrical side wall structure. The strip however includes an externally positioned bendable lip 15 on one end thereof and when it is desired to open such a can, use is made of a detachable manually operated key 16 which is normally carried by the can on the exterior thereof but which may be readily removed to admit of use of the key.

Customarily, the key is provided with a shank 17 in which is formed a longitudinal slot 18. In practice, the key is positioned adjacent to the can so that the lip 15 may be inserted into the slot and bent around the shank. The key is then manually rotated about its long axis so that the tear strip 14 is spirally wrapped about the same. As a result of such wrapping, the strip is torn free from the side wall formation of the can and the top 12 of the can is completely separated from the side wall formation, thus allowing the contents of the can to be readily removed in a well-understood manner.

As previously set forth, it is often a difficult practical matter to operate such a key in a manner confining the strip convolutions to a single plane when wrapped about the key shank. If the convolutions are allowed to slip, it is often difficult to restore the same to a single plane permitting of the tightening thereof about the key shank and the applying of pulling forces to the strip at its region of joinder with the can side wall. As illustrated in the drawing, the present invention provides a guide device capable of ready application to strip-sealed cans of the type set forth and which functions to hold the strip in its properly wrapped positions about the key shank in permitting of a rapid and positive operation in the removal of the sealing strip to open an associated can.

In its presently preferred form, my improved guide device comprises an angular bracket member B which in this instance includes an elongated vertical leg 19 which terminates at its upper end in a shorter horizontally extending leg 20. The latter is formed to include a longitudinally extending centrally disposed slot 21 adapted to receive the shank of the key 16, as shown especially in Figs. 1 and 5 of the drawing. The horizontal leg 20 is widened toward its outer slotted end and carries adjacent its under surface a pair of bead-engaging guide wheels 22 rotatably carried by axle pins 23 depending from the bracket leg 20. The peripheries of the wheels 22 are adjusted to engage the inner surfaces of an upstanding circular bead 24 formed at the juncture of the cylindrical side wall formation of the can with the horizontal top or lid wall thereof.

Also, as shown in Figs. 2 and 3, the vertical leg of the bracket B is formed with an elongated slot 25 for the sliding reception of an outwardly projecting threaded stud 26 carried by the upper end of the vertical arm of an angle member 27, the outer end of the stud being equipped with a wing nut or the like 28 which, when tightened, serves to retain the angle member in various positions of vertical adjustment on the bracket B in adapting the guide device to cans of varying height. Rocking movement of

the angle member relative to the bracket is prevented by providing the vertical arm of said angle member below the stud 26 with a fixed laterally projecting pin 29 arranged within the slot 25.

The horizontally disposed arm of the angle member 27 conforms to the configuration of the bracket leg 20 and has mounted on the upper surface thereof contiguous to its outer end a pair of transversely spaced wheels 30 arranged vertically in registry with the wheels 22, the circumferential portions of the wheels 30 being engaged with the bottom wall 13 of the can shown in Fig. 2 in contact with the inner surfaces of the circular bead 31 uniting the bottom of the can with the side wall thereof. It will be seen that by adjusting the angle member 27 vertically on the bracket B, the lower pair of wheels 30 may be brought into guiding contact with the bottom bead 31 and in a manner compensating for differences in the height of the cans.

The horizontal leg 20 of the bracket B and the corresponding arm of the angle member 27 are slotted as at 32 to slidably receive headed pins or screws 33 carried by guide blocks 34 and 35. The block 34, as it is viewed in Fig. 2, is slidably mounted beneath the bracket leg 20 and is carried by the pins or screws 33. The block 35, as also shown in Fig. 2, is slidably joined through the use of the pins or screws 33 with the upper surface of the horizontal arm of the angle member 27. Both of these blocks are formed with guide recesses 36 for the reception of the spiral windings of the strip 14 of a can as such a strip is being wound about the shank of a key 16. Further, the blocks are vertically slotted as at 37 for the reception of a key shank, as shown more particularly in Fig. 5. To press the blocks 34 and 35 yieldably forward into contact with the can side walls, each block includes a rod 38 which is slidably received in a bore 39 formed in a socket member 40 carried by the vertical bracket leg 19 and the vertical arm of the angle member 27. A coiled expansion spring 41 is interposed between the blocks 34 and 35 and said bracket and angle member and disposed about the block rods 38, so that the expansive force of said springs may be used to press the blocks forwardly and outwardly toward the can side wall structure.

The lower block 35 is somewhat thinner and of less height than the upper block 34. This is done in order that the guide device may be adapted quickly to variations in the positions of the sealing strips provided on different cans. If the sealing strip is disposed well below the bead

24 at the top of a can, as illustrated in Fig. 2, the device is arranged so that the thicker or higher block 34 will be presented in horizontal registry to the strip. If on the other hand the strip is arranged closer to the bead 24, as in Fig. 4, the guide device is inverted with respect to the operating position of Fig. 2 so that the narrow low-height block 35 will be disposed in registry with the removable sealing strip of the can. When such registry has been obtained, the key is inserted in the receiving slots provided therefor and the bendable lip 15 at one end of the strip is engaged with the slot 18 in the key shank 17. Rotation of the key then causes the strip to be wound spirally about the same, with the strip windings confined in the block recess 36, thereby holding the windings, regardless of their increasing diameter as the key is rotated, in said recesses in a manner causing the full and complete removal of the sealing strip from the can structure. Following such strip removal, the top wall or lid 12 of the can is freed from connection with the side wall formations, so that the top wall or lid may be lifted from the can body to provide complete access to the contents of the can.

I claim:

A guide appliance for use in the opening of key-actuated strip-sealed metallic containers, comprising: a frame 25 adapted to be arranged at the side of such a can and to rotate bodily around the same, said frame including vertically spaced inwardly and horizontally directed arms arranged to receive between them the ends of said container; wheel means carried by the arms, said means being engageable with annular beads formed on the ends of said containers; and spring-pressed guide blocks slidably carried by said arms for movement toward and away from vertical side wall formations of said container in which removable sealing strips of the container are disposed, said blocks being formed with recesses adapted for registry with said strips to receive the latter when the same are wound about the shanks of turnable keys joined with said strips and rotatably and removably positioned in vertically registering openings formed in said arms and blocks.
